(57) **CLAIM**

The ornamental design for infant garment, as shown and described.

DESCRIPTION

FIG. 1 is a front elevation view illustrating my design for infant garment;

FIG. 2 is a right side view thereof;

FIG. 3 is a rear elevation view thereof;

FIG. 4 is a left side view thereof;

FIG. 5 is a rear elevation view thereof;

FIG. 6 is a left side view thereof; and,

FIG. 7 is an interior perspective view taken from FIGS. 5 and 6 thereof.

The broken lines shown illustrate portions of the infant garment that form no part of the claimed design.
